UNITED STATES PATENT OFFICE.

PAUL GROEBER, OF RUTHERFORD, NEW JERSEY, ASSIGNOR TO HENRY M. BIRGE, OF BUFFALO, NEW YORK.

DESIGN FOR WALL-PAPER.

SPECIFICATION forming part of Design No. 26,123, dated September 29, 1896.

Application filed August 24, 1896. Serial No. 603,776. Term of patent 3½ years.

To all whom it may concern:

Be it known that I, PAUL GROEBER, a citizen of the United States, residing at Rutherford, in the county of Bergen, in the State of New Jersey, have invented and produced a new and original Design for Wall-Paper, of which the following is a specification, reference being had to the accompanying drawing, showing a part thereof.

10 The design consists of an irregular arrangement of long sprays of roses and leaves and fern-like grass, as represented in the accompanying drawing.

The border for the said design also consists of sprays of roses and leaves and fern-like grass arranged in an open wreath-like form, as shown in the drawing.

What I claim is—

1. The design for wall-paper herein shown and described.

2. In the design for wall-paper the border herein shown and described.

Witness my hand this 19th day of August, 1896.

PAUL GROEBER. [L. S.]
